UNITED STATES PATENT OFFICE.

PAXTON POLLARD, OF NORFOLK, VIRGINIA.

DESIGN FOR A BADGE.

SPECIFICATION forming part of Design No. 18,826, dated December 25, 1888.

Application filed November 16, 1888. Serial No. 290,973. Term of patent 7 years.

To all whom it may concern:

Be it known that I, PAXTON POLLARD, a citizen of the United States, and a resident of Norfolk, in the county of Norfolk and State 5 of Virginia, have invented a certain new and original Design for a Badge; and I do declare the following to be a full, clear, and exact description of the invention, such as will enable others skilled in the art to which it appertains 10 to make and use the same, reference being had to the accompanying drawing, and to letters or figures of reference marked thereon, which form a part of this specification.

The drawing is a representation of this 15 design and is a front view.

My design is for a badge, and its features are shown in the accompanying drawing.

The letters A A indicate two flag-staffs crossed and provided with spear-heads and 20 cross-bars below said spear-heads, as shown.

The flags B and C are represented attached to said staffs and hanging outward and downward therefrom in a waving manner, their end portions being curled back. Each flag 25 has along its upper edge and extending downward in curved form around its upper and

outer corner portion a serpentine marginal stripe, a', and has a serpentine stripe, a, extending along its lower border to the lower and outer corner of the flag, where it is separated from the flag by a rounded shade-spot, Z. The flag B has between the stripes a and a' the cross-stripe c, which is marginally bordered with white, and has thirteen stars arranged thereon, as shown. The fields b are of 35 triangular form, as indicated.

The flag C has between its stripes a and a' the rectangular field of stars d in one corner and the three broad stripes e e f, arranged as shown, the lower stripe, e, being separated at 40 its end from the margin a by the shade-spot Z, as shown.

What I claim is—

The design for a badge, substantially as herein shown and described.

In testimony whereof I affix my signature in presence of two witnesses.

PAXTON POLLARD.
